UNITED STATES PATENT OFFICE.

FILIPPO SANTORO, OF HOLYOKE, MASSACHUSETTS.

EXTENSION-TABLE.

1,392,527.

Specification of Letters Patent.

Patented Oct. 4, 1921.

Application filed June 16, 1920. Serial No. 389,468.

To all whom it may concern:

Be it known that I, FILIPPO SANTORO, a subject of the King of Italy, and resident of Holyoke, in the county of Hampden and State of Massachusetts, have invented certain new and useful Improvements in Extension-Tables, set forth in the annexed specification.

My invention relates to tables of the extension, circular top type, and one of its purposes resides in the provision of an arrangement embodying a plurality of leaves or top sections so shaped and adapted to be so associated with two or more tables having circular tops that an elongated table may be produced having either angular or curved ends. Further, it is a purpose of my invention to so shape these leaves or top sections that a single circular table may be converted into a rectangular table, and still further it is one of my purposes to provide a construction which will permit of the circular top tables produced in accordance with my invention being used singly and independent of the leaves or top sections.

Further it is a purpose of my invention to provide a construction allowing facility and compactness in arranging the parts of my improved table for transportation and storage.

My invention consists in the peculiar construction, combination and arrangement of parts to be hereinafter more fully set forth in connection with the accompanying drawings which are illustrative of the best embodiments of my invention known to me at present, but which are, however, susceptible to modification and change with the exercise of only ordinary mechanical skill and without departing from the scope of the invention as set forth in the appended claims.

In the drawings:

Figure 1 is a top plan of a table having a top constructed in accordance with my invention;

Fig. 2 a similar view of another table top;

Fig. 3, a side elevation of the table illustrated in Fig. 1;

Fig. 4, a side elevation of the table illustrated in Fig. 2;

Fig. 5, a bottom plan of the table illustrated in Fig. 2;

Fig. 6, a perspective of one of the filler blocks;

Fig. 7, a top plan showing the manner of

connecting the two tables illustrated in Figs. 1 and 2 to produce an elongated table having curved ends;

Fig. 8, a top plan showing the manner of producing a rectangular table from the table illustrated in Fig. 1;

Figs. 9, 10 and 11, perspectives of other filler blocks used in connection with the tables illustrated in Figs. 1 and 2; and

Fig. 12, a section showing the manner of arranging the tables for transportation and storage.

Referring to the drawings in detail A and B designate, respectively, as illustrated in Figs. 1 and 2, two tables, the former including a circular top 10 and the latter a circular top 11.

The under face of the top 10 of the table A is recessed at 12 and within this recess, near its ends, are pivoted the legs 13 of this table, said legs when swung to folded position lying entirely within said recess as best illustrated in the sectional view Fig. 12. Likewise the under face of the top 11 of table B is recessed at 14 to receive the pivoted legs 15 of this table. Top 10 of table A at evenly spaced points in its upper face is provided with recesses 16 which open into the peripheral edge and are of a depth somewhat less than the thickness of the top so that shelves are thus formed with their upper faces disposed below the plane of the upper face of the table top. Extending upward from each of these shelves is a pair of spaced pins 17. Certain of the shelves are recessed to receive supporting members 18 in the form of flat preferably metallic bars, pivoted at one end to the shelves so as to be permitted to swing outwardly therefrom. At their other ends these bars are provided with screw fasteners 19 for a purpose which will later appear.

Preferably the table top 10 is provided with six recesses and table top 11 with but three recesses similar in all respects to the recess of top 10 with certain of them provided with bars similar to the bars 18 of recesses 16 and each of them provided with spaced pairs of pins similar to the pins 17. Aside from the difference in the number of recesses in the upper faces of their tops the two tables A and B are of exactly similar construction with the further exception that table B is provided on its under face with a narrow ring 20 disposed near its

periphery and forming a means of maintaining the table tops in spaced relation when top 11 is arranged upon top 10 as shown in Fig. 12 of the drawings, the ring 5 at diametrically opposite points being provided with projections 21 of a shape and size to snugly fit a pair of diametrically opposed recesses 16 in top 10 when the tables are so arranged in order to hold them in 10 properly assembled relation. The projections 21 are provided with openings properly spaced to receive the pins 17 when the tops are superposed as will be understood.

In conjunction with the tables just described I employ filler blocks 22 of a size and shape to fit the recesses 16 and to provide a smooth unbroken top and peripheral surface for either of the tables when it is desired to use the same as an independent 15 circular table. These filler blocks are provided with openings 23 to be engaged by the pins 17 to maintain the blocks in place.

When it is desired to produce from the table A a table having a rectangularly shaped 20 top, as illustrated in Fig. 8, I employ filler blocks such as are illustrated in Figs. 6 and 11, the latter consisting merely of rectangular blocks 24 shaped to fit the recesses 16 and provided with openings 25 to receive the pins 17, and the former consisting of blocks 26 having a portion 27 shaped to fit the recesses 16 with another portion curved 25 as at 28 to engage the periphery of the top adjacent the recesses. Each of these blocks 30 includes a main body portion 29 of angular shape so that when four of them are associated with a corresponding number of the recesses 16 and a pair of the blocks 24 are associated with the two remaining recesses, 35 as shown in Fig. 8, a rectangular table is provided having substantially the same dimensions as the circular table, the outer edges of the blocks 24 and 26 forming an unbroken peripheral and upper surface extension of each other as well as with the 40 top 10. When the filler blocks are so arranged the bars 18 are swung out on their pivots so as to underlie and support the blocks 26 to which they may be secured by 45 the screw fasteners 19.

When the two tables A and B are arranged 50 side by side as shown in Fig. 7 they may be connected by a block 30 which is of rectangular shape and of a size to fit respective recesses in the two tables, openings 31 being provided therein to receive the pins in the recesses and when this is done the filler blocks 26 may then be associated with the two tables in the manner previously set forth 55 to fill the spaces between the tables and thus provide an elongated table the sides of which are straight and form an unbroken continuation of the curved edges of the tops 10 and 60 11.

When the two tables A and B are so 65 associated the unused recesses of table top

10 may be filled by the fillers 22 or by fillers 26 and 24 as may be desired to provide either a table having one end curved and the other angular or both ends curved. On the other hand if two tables similar to table A are 70 so associated they may be converted into a single elongated table of rectangular shape by associating with both ends as well as between them, blocks such as those illustrated at 26.

When it is desired to compactly assemble the parts of my table for transportation or storage the top B may be arranged upon the top A with the projections 21 engaging a pair of recesses 16 and the ring 20 maintaining the tops in spaced relation so that a space 80 is thus provided between them to conveniently receive the filler blocks.

I claim—

1. The combination with a circular table 85 top of filler blocks shaped for coöperation with said circular top to produce an angular table top.

2. The combination with a circular table top, of filler blocks shaped for coöperation 90 with said circular top to produce a rectangular table top having substantially the same dimensions as said circular top.

3. The combination with a circular table top provided with recesses, of filler blocks 95 shaped for coöperation with said circular top and said recesses to produce an angular table top.

4. The combination with a circular table top provided with recesses, of filler blocks 100 shaped to coöperate with said circular top to produce an angular table top, portions of said blocks seating in said recesses, and means securing portions of said blocks in said recesses.

5. The combination with a table top, a portion of the periphery of which is curved, of means coöoperating with said curved periphery to change the shape of said top.

6. The combination with a recessed table 110 top of predetermined shape, of filler means for said recesses coöoperating with the periphery of said top to change its shape.

7. The combination with a circular table top provided with a plurality of recesses 115 in its upper face near its periphery, of filler blocks shaped to engage with the curved peripheral edge of the table top and with said recesses, and another filler block shaped to engage with one of said recesses and form 120 a continuation of an edge of one of said first filler blocks.

8. The combination with a pair of tables having circular tops and arranged side by side, of filler blocks arranged between said tables and forming an unbroken straight edge between the curved edges of said circular tops.

9. The combination with a pair of tables having circular tops and provided with a 130

plurality of recesses in their upper faces near their peripheral edges, of a rectangular block fitting a recess of the respective tops and securing the tables together, and other 5 blocks between the tables and forming an unbroken straight edge between the curved edges of said circular tops.

In testimony whereof I hereunto affix my signature in the presence of two witnesses.

FILIPPO SANTORO.
